UNITED STATES PATENT OFFICE.

PHILIP COLLINS STEVENS, OF SPRINGFIELD, MASSACHUSETTS, ASSIGNOR TO A. G. SPALDING & BROS., OF NEW YORK, N. Y., A CORPORATION OF NEW JERSEY.

SKATE-SHARPENING DEVICE.

Application filed January 31, 1929. Serial No. 336,549.

My said invention relates to skate sharpening tools or devices of the type in which a carrier adapted to be grasped by the hand is provided with an abrasive surface and guides 5 whereby it is adapted to be reciprocated along the edge of the blade for sharpening it.

The invention aims to provide a simple and efficient device for this purpose which can be manufactured at an extremely low cost.

10 It further aims to provide a device in which emery cloth is used for the abrasive material and one in which the cloth may be readily shifted when worn, to bring a fresh portion or portions of the cloth into position for 15 action on the blade.

With these and other objects in view, the invention includes the novel features of construction and arrangement and combination of parts hereinafter described, the invention 20 being defined by the claims appended hereto.

An embodiment of the invention is illustrated in the accompanying drawing in which:

25 Figure 1 is a side elevation of the device shown in operating position in connection with the dotted outline of a skate blade.

Fig. 2 is a section on line 2—2 of Fig. 1 on a larger scale.

30 Fig. 3 is a detail view showing the several parts separated and in perspective.

Fig. 4 is a plan view of the main carrier element partly in section.

Referring by reference characters to this drawing, the numeral 1 designates a plate member of a thickness approximately that of the skate blade A and having a straight lower edge 1^a and outwardly and downwardly curved flanges 1^b. This member may be conveniently and expeditiously formed from a 35 blank of sheet metal folded upon itself and having the juxtaposed portions between the edge 1^a and the flanges 1^b brazed or welded together. Preferably the flanges extend slightly beyond the ends of the body portion, 40 as shown. 2 designates the main body of the device which is likewise of sheet metal (of a lighter gage) and which is bent to form a substantially cylindrical portion 2^a and substantially parallel portions 2^b having inwardly 45 deflected lower edge portions 2^c firmly held in spaced relation by spacing blocks 2^d and rivets 2^e.

The cylindrical portion 2^a is provided with an elongated slot a to receive the plate member 55 1 and the emery cloth 3 which is doubled

over the edge 1^a of the plate member and extends up the sides thereof. The flanges 1^b are curved to correspond to the curvature of the cylindrical portion 2^a and when the plate member has been inserted in the slot, the marginal portions of the emery cloth lie between the inner faces of the curved flanges and the outer face of the cylindrical part.

For clamping the parts in their assembled condition, I provide a clamp in the form of a split tube 4 of resilient sheet metal, the slit 4^a of which corresponds in width to the distance between the external faces of the parallel portions or guides 2^b. This clamp is slid endwise onto the assembled parts above referred to and clamps them firmly together. the sleeve constituting the part which is grasped by the hand for reciprocating the device along the blade. During such reciprocation, the portions 2^c constitute guides to 70 engage with opposite sides of the skate blade to prevent lateral movement of the device during its rectilinear movement. Skate blades are customarily made somewhat flaring or of slightly dove-tailed shape adjacent the edge of the skate blade or runner and the inward deflection of the guide portions accommodates them to this shape and prevents any lateral rocking motion. The said guides being of spring or resilient metal can accommodate themselves to slight inequalities or differences in thickness of blades.

With the parts assembled as above described, the device can be easily manipulated to sharpen skates until the active portion of the emery cloth is too much worn to become effective. To bring a fresh portion into active position, it is only necessary to slide the clamp off, withdraw the plate member, shift the emery cloth and reassemble the parts.

Having thus described my invention, what I claim is:

1. A skate sharpening device comprising a member having parallel guides and a head provided with a slot alining with the space between said guides, a plate member, a sheet of abrasive material doubled over said plate member, said plate member and sheet being inserted through said slot into the space between said guides, and means detachably engaging said head for holding the parts together.

2. A skate sharpening device comprising a body member having parallel guides and a head provided with a slot alining with the

space between said guides, a plate member projecting through said slot into the space between the guides, an abrasive sheet overlying the plate member between the guides, 5 said plate member having flanges overlying the head of the body member, and means for clamping said head and flanges together.

3. A device according to claim 2 in which the body member comprises a single piece of 10 sheet metal bent upon itself to form a head and spaced parallel guide flanges.

4. A device according to claim 2 in which the body member comprises a sheet metal blank bent to provide a head and spaced parallel guide flanges, the lower edges of the 15 guide flanges being deflected inwardly towards each other.

5. A device according to claim 2 in which the clamping means comprises a split resilient sleeve slidably embracing the head and flanges. 20

6. A device according to claim 2 in which the head is made of approximately cylindrical shape and the flanges are curved to fit the same, and the clamping means comprises 25 a split cylindrical sleeve of resilient sheet metal.

7. A device according to claim 2 in which the plate member comprises a single sheet of 30 metal folded upon itself and having juxtaposed parts rigidly secured together and outward turned marginal parts forming the flanges.

In testimony whereof I affix my signature.

PHILIP COLLINS STEVENS.
